CLAIM

The ornamental design for reconfigurable and flush, side windows and pillars of automotive vehicle, as shown and described.

DESCRIPTION

FIG. 1 is a front perspective view of reconfigurable and flush, side windows and pillars of automotive vehicle, of the new design, with the side windows in raised positions; FIG. 2 is a rear perspective view thereof; FIG. 3 is a side view thereof; FIG. 4 is a top view thereof; FIG. 5 is a side view thereof, opposite that of FIG. 3; FIG. 6 is a front view thereof; FIG. 7 is a rear view thereof; FIG. 8 is a bottom view thereof; FIG. 9 is an enlarged partial front view thereof, taken within the dashed circle in FIG. 6; FIG. 10 is an enlarged partial rear view thereof, taken within the dashed circle in FIG. 7; FIG. 11 is an exterior surface view, taken along horizontal line 11-11 from FIG. 3, showing the flushness of exterior surfaces of the raised side windows and pillars; FIG. 12 is a side view thereof showing front and rear door side windows in lowered positions; and, FIG. 13 is a side view thereof, opposite FIG. 12, showing front and rear door side windows in lowered positions. The broken lines illustrate the environment in which the design is embodied and portions of the reconfigurable and flush, side windows and pillars of automotive vehicle which form no part of the claimed design.
